UNITED STATES PATENT OFFICE.

GUY M. HALLAM, OF MONTCLAIR, AND EDWARD POST, OF NEWARK, NEW JERSEY.

GAME.

Application filed January 10, 1923. Serial No. 611,833.

To all whom it may concern:

Be it known that we, GUY M. HALLAM and EDWARD Post, citizens of the United States, residing at Montclair and Newark, respectively, county of Essex, and State of New Jersey, have invented certain new and useful Improvements in Games, of which the following is a specification.

This invention relates to improvements in games and particularly to that type of game played by two parties upon a level board by moving figural objects thereover in accordance with certain definite rules.

The object of the invention is to produce a novel game which is enjoyable to the young and old of both sexes alike, the game inculcating memory and a certain degree of skill, matching as it does the ability of one player against the other.

This object is accomplished by the novel arrangement and disposition of localities on the face of the board and by the articles movable thereon as operated by certain definite rules for playing, as will hereafter be set forth and illustrated in the accompanying drawing, the same being a face view of the board with certain of the movable articles thereon.

The board, generally designated by the numeral 5, is preferably rectangular as shown, has a level upper surface and may be made of wood, metal or fibre, as may be desired.

At the ends are blank spaces 6 and 7 which may be utilized for advertising purposes, to bear the rules of the game or other similar displays.

The opposing players face the sides of the board and adjacent the edges are rows of circles or spots 8 and 9 on which are originally disposed the units or checkers 10 and 11 respectively for each player, these units being of different colors, as red and black, so as to be readily distinguished, one side from the other.

In playing the game it is preferred to call the circles or spots in the first rows barracks, the units or checkers being regarded as private soldiers; the interjacent rows of circles or spots are known as stations and decrease in number by one until the sixth which has the same number as the fourth.

Intermediate the inner rows of circles or spots are ovals or spots 12 which differ in contour from the spots 8 and 9 and repre-

sent trenches, one at each end, and between said ovals or spots 12 are hexagonal figures or spots 13 representing forts, in which are mounted guns 14, the board being regarded as a battlefield.

At the beginning of the game each player mounts the allotted twelve soldiers in the outer row of spots 8 and 9.

Either player may start by moving one of the private soldiers diagonally into the next adjacent row, one space at a time, as in the well known game of checkers, such move to be followed by the other player alternately, and in so moving may jump the opponent's private soldier that may be in his path.

When a Private has moved into one of the forts or through either of the trenches, he then becomes a Lieutenant and is represented by two playing units, one on top of the other (just as a checker is crowned king). As a Lieutenant he may move and may jump opposing soldiers in four directions, namely; diagonally forward in both directions like the Private and directly to the right and to the left.

Continuing on, as a Lieutenant moves into the opponent's barracks he becomes a Captain and is represented by three playing units, one more on top of the other two. A Captain may move and may jump opposing soldiers in any and all of the six directions on the board, namely diagonally forward in two directions, diagonally backward in two directions and directly to right and left. He cannot, however, jump a Private in the Private's own barracks, though he may jump an opposing Captain there. A Lieutenant or Captain cannot jump an opponent from the forts to the trenches or vice versa, but he may do so in the forts.

The rules for moving and jumping are in general the same as of the game of checkers.

The Private may jump only in a diagonally forward direction and in a double-jump or triple jump, may jump diagonally right forward and then diagonally left forward, and so continue, or diagonally left forward then right forward, etc.

A Lieutenant may make a double, triple, or quadruple jump directly right then diagonally left then, diagonally right then directly left or over any other combination of these directions.

A Captain may make a double, triple,

quadruple, quintuple or sextuple jump directly right, then diagonally right forward, then diagonally left forward, then directly left, then diagonally left, backward, then diagonally right backward to the station on which he started or over any other combination of these directions.

A soldier may move into a trench only relative to the sides of said board. 2. A game comprising a board having from the station directly above the trench or the station directly below it, and he cannot be jumped while occupying any of these four stations above and below the trenches, though he may be jumped in the trench itself. 15 However, he cannot move into one of these stations if the station on the other side or the trench itself is occupied by a Private or a Lieutenant, though he may move into it if it is occupied by a Captain.

20 Every soldier must jump an opposing soldier when there is an opportunity to do so, and as a penalty for not doing so he may be removed from the board by the opposing player.

25 When the game reaches a point where there are two players left on the board on one side and only one on the other, if the one player enters the pass and his opponent enters the pass on either side of the board, only to jump. In the event of only one player being left on either side, the game is a tie.

From the foregoing it will be seen that the game is well adapted to be played by all kinds of people and that the playing is instructive as well as amusing, because of the necessity of memorizing the rules of the game, studying the best possible moves to make and considering the effect such moves will have on the action of the opponent and subsequent results.

Having thus described our invention and set forth the manner of its application, what we claim as new and desire to secure by Letters Patent, is:

1. A game comprising a board having a plurality of rows of circles disposed on each side thereof, the number of circles decreas-

ing from the edges toward the center in each row, an additional circle in the innermost rows, a central row of polygonal figures, elliptical figures at the ends of said central row, and a plurality of objects movable on the circles and, figures of said board, said objects being distinguished by color

2. A game comprising a board having blank spaces at its ends, a row of twelve spots adjacent its side edges, rows of eleven, ten, nine, eight and nine spots adjacent said outer rows, a row of six spots of different value intermediate the inner rows of nine

spots; a spot of another value at each end of the row of last named spots, and two different sets of twelve objects movable in a pre-determined manner over the face of said board.

3. A game comprising a board having clear spaces at its ends, a plurality of figures inscribed on said board, said figures being disposed in longitudinal and obliquely transverse rows, the outermost rows repre-

senting a certain value, the innermost row representing different values, its end eleven on one side and only one on the other, if the one player enters the pass and his opponent forces him out, he cannot again enter the pass on either side of the board, the two different sets of objects transversely to the innermost row a still different value, and only one player being left on either side, the game is a tie.

4. In a game, a playing surface having two separate sets of independent spots thereon, arranged in symmetrically diminishing formation towards the center, a row of spots of a different value separating the sets of spots, a spot of still another value at each end of the intermediate row of spots, and playing pieces adapted to be moved over said playing surface.

This specification signed and witnessed this 9th day of January, 1923.

GUY M. HALLAM,
EDWARD POST.
